UNITED STATES PATENT OFFICE.

VINCENT E. KEEGAN, OF BOSTON, MASSACHUSETTS.

ELECTRIC MOTOR.

SPECIFICATION forming part of Letters Patent No. 349,654, dated September 21, 1886.

Application filed February 4, 1886. Serial No. 190,865. (No model.)

To all whom it may concern:

Be it known that I, VINCENT E. KEEGAN, a citizen of the United States, residing at Boston, in the county of Suffolk and State of Massachusetts, have invented a new and Improved 5 Electro-Magnetic Motor, of which the following is a specification.

The nature of my invention consists in the peculiar construction of the pole ends of the 10 field-magnet cores, which face each other on a parallel line, and the arrangement of one or more double electro-magnet armatures to rotate on a line parallel and common with the axis of said pole-cores of field-magnet, so that 15 the armature simultaneously moves by attraction and repulsion from its present position to one before the peculiarly-constructed pole. The object of this is to make one field-magnet equivalent to a number of separate magnets, 20 while in reality but one magnet is used, whose poles are crowned, all as described in the following specification.

In the accompanying drawings, Figure 1 is a perspective view of the motor. Fig. 2 shows a modified form of armature detached. Fig. 3 shows in side elevation the armature in position. Fig. 4 shows in perspective a modified form of the field-magnet. Fig. 5 shows the armature in its relation to this form of field- 30 magnet, and Fig. 6 is a face view of Fig. 4.

In Fig. 1 I show a full view of the motor. A A' are the two poles of a field-magnet. These are preferably hollow cylinders of about five 35 inches in diameter, five inches long, and the walls from one-half to one inch in thickness, as shown by letter H on the face of the pole in Fig. 4. These dimensions may be varied according to the size of the motor. I place the crown-points or projections, Figs. 1 and 40 3, m m m m and n n n n, on the end of said hollow cylindrical poles around the circumference. I place the crown-points on one pole, A, so that they come opposite the spaces between the crown-points on the pole A'. Although I 45 show the crown-points and the spaces between such points on each pole of equal width, the one may be in excess of the other when two or more armatures are used—that is, the spaces between the crown-points may be greater or 50 less than the width of each point or projection; but I prefer to use them as described. These poles, with their crown-points or pro-

jections, as shown in Fig. 1, face each other on a parallel line with a common axis to each, and s s s represent the back-piece and frame of 55 such motor. On the shaft K K K, common with said axis of the magnets, I adjust the armature d d' e e' i i', which is a double electro-magnet, or two electro-magnets with their backs to each other, and is placed between the 60 poles A A' of the field-magnet. The poles of the armature are of the same diameter as the width of the crown-points, and of about two inches in length up to the back piece i i', and act before the poles of the field-magnets as fol- 65 lows: The poles d d' are both of the same sign, or both north poles, and e e' are both south poles; but d e constitute one electro-magnet, and d' e' another magnet, making them distinctly two electro-magnets separate from each other. 70 When d and d' are north poles and A of the field-magnet is south pole, then A' of field-magnet will be north pole. Therefore d, which is north pole with d', will attract crown-point n of pole A, while d' will repel n of A', and 75 when d' is flush with the space between the crown-points on pole A' and d is flush with n of pole A, then the armature changes polarity through and by its coils, which are connected with a commutator to so act. Such 80 commutator I need not here describe, as it is of the ordinary make to accomplish such change of direction of current. While d and d' thus act as described, e and e' act correspondingly on the other half of the cylindrical 85 core of the field-magnet, and thus as the armature attracts and repels simultaneously on each of its pole sides, and successively changes polarity when flush with each one of the crown-points, it acquires a rotary motion on 90 its shaft, which for direction of motion much depends upon its momentum, to give it direction of attraction one way or another over the opposite, which is sufficient in and for small motors; but in the large motor, to be inde- 95 pendent of momentum altogether, I use two of such double electro-magnet armatures as described, which I show in Fig. 2, d d e e. In this figure, d e is one electro-magnet of north pole d e south pole, and the cross-bar or 100 right-angle piece with poles d e represents a second electro-magnet. Back to back with these two magnets are two corresponding electro-magnets, as d' e' and d' e', so the four con-

stitute two double electro-magnets or four magnets placed back to back and at right angles to each other. In Fig. 3 I show this armature adjusted on the shaft or in position it would be when on the shaft and between the poles of the field-magnet, the same as previously described, $A A'$ being field-magnet poles and $d' d' c' c' e' e'$ representing the poles of such armature, and $i' i'$ being their cross-pieces.

When d' is flush with m , c' of the second double armature is half flush with m'' , and, therefore, as it has the way of motion by one-half the length of a width of crown m'' , it adds its force of attraction to m'' over its attraction to m' , and the force of attraction of d to n of pole-piece A , thereby giving $d' e'$ a greater attraction to $n m'$ in the direction of the motion of c' than in the opposite direction. Thus as one of the double armatures is always one-half ahead over one of the crown-points, there is always a greater force of attraction in one given direction, causing the armature to make a complete rotation independent of momentum and without any dead-centers of motion. I thus obtain, by the successive changes of polarity of the armature through its commutator connected with its coils, a rotary motion of such armature on its shaft between the two poles of one field-magnet only, whose pole ends having the crown-points, as described, they are substantially equivalent to an equal number of separate field-magnets. Thus I am able to obtain a large motor in a small space and at much less cost of material and less weight.

The cylindrical cores of the field-magnets $A A'$, I wind with covered wire, as shown in the drawings, which makes them electro-magnets. I also, as shown, wind the armature-poles with wire, which may be or not in the same circuit with the coils of the field-magnet; but I prefer them to be independently connected with a commutator.

In Fig. 4 I show a modified form of the motor described in Fig. 1. In this figure, A represents one cylindrical hollow core, with its crown-points $n n n n n n$, and also wound with wire; and B represents the other pole, which I place within the pole A and concentric with it, having also its crown-points $m m m m m m$. These two poles are united by the back pieces $s s$ and foot-stand s' . Between these two poles A and B , and within the space R , I insert the poles of an ordinary horseshoe electro-magnet to about one inch, as shown in Fig. 5, where $E E$ is such an armature, with its poles inserted in such space R between the said poles A and B ; and $K K$ is the shaft on which it rotates, one end of which sets into B for support. The inner pole, B , of the field-magnet I show with a wire coil around it in perspective in Fig. 4, and in Fig. 6 I show a face view of the two pole ends of A and B ,

with a sectional view of the armature-poles E inserted within the space R between said poles A and B , and the action of the armature between the two poles of the field-magnet is substantially the same as that described for the motor shown in Figs. 1 and 3—that is, when the armature-poles attract n of the outer pole of the field-magnet they repel m of the inner pole. If E attracts n , it repels m , and when attracting m it repels n , and by changing polarity when flush with m or n it then acts by attraction or repulsion to the next succeeding crown-point, and so on during a full revolution.

In the diagram I show but one armature; but in the large motor for practical power I would use two or more, placing the second armature so that it would overlap one-half the face of the crown-point or projection n and m , the same as described in the foregoing for the armature in Figs. 2 and 3; but whereas in these figures I show double armatures, in the present form of Figs. 4, 5, and 6 I would only use one or more single electro-magnet armatures, as shown in Figs. 5 by $E E$.

I claim as my invention—

1. In combination, the cylindrical cores of a field-magnet having crown-pieces, and an armature on the same axis as the cylindrical cores, with poles of a diameter equal to the width of one of the crown-pieces and parallel therewith, adapted to revolve by successive attractions and repulsions before one crown-piece of each cylindrical core at a time for each individual electro-magnet of the armature, substantially as described.

2. In combination, the cylindrical cores of a field-magnet having crown-pieces equal in width to the spaces between them, and an armature on an axis concentric with the cores, and having poles equal in diameter to the width of one crown-piece, adapted to revolve by attractions and repulsions before one crown-piece of each cylindrical pole at a time for each individual electro-magnet of the armature, substantially as described.

3. In combination with the hollow cylindrical cores having crown-pieces, the double armature having pole-pieces revolving on axes concentric with that of the cylindrical cores and in front of the crown-pieces, said armatures being placed back to back, all substantially as described.

4. The hollow cylindrical core of a field-magnet having crown-pieces, in combination with an interior core with the crown-pieces and an armature, all substantially as described.

VINCENT E. KEEGAN.
